UNITED STATES PATENT OFFICE.

PETER TAYLOR, OF PAWTUCKET, RHODE ISLAND, AND WILLIAM A. GOVE,
OF CHARLESTOWN, MASSACHUSETTS.

IMPROVED BED-BOTTOM.

Specification forming part of Letters Patent No. 55,390, dated June 5, 1866.

To all whom it may concern:

Be it known that we, PETER TAYLOR, of Pawtucket, of the county of Providence and State of Rhode Island, and WILLIAM A. GOVE, of Charlestown, in the county of Middlesex and State of Massachusetts, have invented an Improved Spring-Bed Foundation; and we do hereby declare the same to be fully described in the following specification and represented in the accompanying drawings, of which—

Figure 1 is a longitudinal section, and Fig. 2 a transverse section, of it.

In carrying out our invention we make use of a light frame, A, composed of a series of thin spring-slats, *a a a*, and two or more connecting-slats, *b b*, the said slats *a a a* being arranged parallel to each other and at equal distances apart, and being connected at or near their ends by the transverse slats *b b*.

A series of brackets or arms, C C C, project downward from the said frame A, close to each end of it, each of the said brackets or arms being provided with a buckle, *c*, for connecting it with one of a series of vulcanized india-rubber elastic straps or springs, D. Each of the said springs, after having been buckled to its arm, extends upward alongside of the said arm, and from thence is led over and half-way around a roller, E, from which the strap or spring descends, and is fastened to the lower part of a plate, F, which serves to support the axle of the roller, and is screwed to a bed-frame, B, the whole being arranged

substantially in manner as represented in the drawings. The frame A, which is for sustaining a mattress or bed, thus becomes supported by means of a series of elastic strips of india-rubber, which, by being carried around rollers and fastened to the frame B, become arranged so as to operate to excellent advantage.

By means of the buckles the elastic straps may be taken up so as to vary the degree of elasticity as occasion may require, and particularly in order to prepare the bed-foundation for the support of two persons, one of whom may be heavier than the other.

We claim—

1. The combination and arrangement of the arms C, projecting from the frame A, with the elastic or india-rubber straps and their supporting-rollers, applied to the frame B, the whole being substantially as specified.
2. The combination of the buckles or equivalent take-up mechanism with the arms C and the elastic strips, applied to the frames A and B, substantially in manner as specified.
3. The combination of the straining-plates F, the elastic straps or springs, their supporting-rollers, and the arms C, the whole being arranged together and with the frames A and B, substantially in manner and so as to operate as specified.

PETER TAYLOR.
WILLIAM A. GOVE.
